UNITED STATES PATENT OFFICE.

ERLE KING BAKER, OF CHICAGO, ILLINOIS, ASSIGNOR TO BAKER WHEEL & RIM COMPANY, OF CHICAGO, ILLINOIS, A CORPORATION OF ILLINOIS.

ART OF MANUFACTURING WHEELS.

1,368,420.

Specification of Letters Patent. Patented Feb. 15, 1921.

Application filed December 3, 1919. Serial No. 342,189.

To all whom it may concern:

Be it known that I, ERLE KING BAKER, a citizen of the United States, and a resident of Chicago, county of Cook, and State of Illinois, have invented certain new and useful Improvements in the Art of Manufacturing Wheels, of which the following is a specification.

My invention relates to motor vehicle wheels of the kind that are equipped with pneumatic tires; and in particular, it has to do with wheels of that class which I have made known as "semi-wood wheels."

The object of my invention is so to improve the art of manufacturing such wheels that the time of making the same shall be reduced, the cost reduced and the inherent elasticity and resilience of the wheel improved and advantageously utilized.

A so-called semi-wood wheel of my invention has radial spokes which are made of hickory, or other sufficiently strong and resilient wood, and these spokes bear an endless, metal fixed rim, without the interposition of a separate felly. Whatever the method followed in assembling the spokes within the endless rim, I have found, as set forth in my Patent No. 1,324,293 of December 9, 1919, that it is desirable frequently and indeed usually desirable to positively swage, compress or upset the fixed rim circumferentially after it is placed on the spokes in order to insure the circularity of the wheel, give it the circumference suited to the tire to be used, and also to more firmly force the inner ends or butts of the wooden spokes together, this last being for the purpose of converting such butts into an all-wood hub center of substantially uniform density throughout, and hence providing best possible foundation or base for the remainder of the wheel.

This invention as compared with that of said Patent No. 1,324,293, comprises an intermediate step or accomplishment whereby the fixed metal rim (after being circumferentially upset and then released from the swaging tool) is prevented from such molecular recovery of reaction as would tend to increase its effective circumference and diminish its pressure upon the spokes.

The nature of my invention and the means by which it is carried into effect will be readily understood on reference to the accompanying drawings;—in which, Figure 1 is a

plan view of the typical wheel of my invention, shown in assembled condition within the group of radially movable jaws of the upsetting press; the full lines showing the completed operation and the dotted lines 60 showing the parts before the press has started its compressing stroke;—Fig. 2 is a plan or side view of the completed wheel where-in the endless metal felly has recovered its substantially true circularity; Fig. 3 is an 65 enlarged view of a peripheral section of the wheel, taken from Fig. 1, that is, as the parts appear while in the press;—Figs. 4, 5, 6, 7, 8, 9 and 10 are cross-sectional views exemplifying various shapes in which the fixed rim 70 of the wheel may be made, all thereof being such as to adapt them to yield to the compression herein described, without material distortion from the shape in which they are originally hooped up, welded and rolled. 75

Referring to the drawings for typical details of construction:—The parts, 3, are wooden spokes having mitered butts, 3', forced together which center contains the hub hole, 4. The peripheral part, 5, is an 80 endless ring of metal of such thickness and so flanged as to resist circumferential elongation, radial distortion and lateral distortion by any of the forces which may be exerted thereon by or through the spokes, 3, or 85 by the tire which the part, 5, carries. This part, 5, is called the fixed rim of the wheel. As suggested in Figs. 4 and 5 it may have flanges adapting it to hold a pneumatic tire, or, as suggested in Figs. 6 and 10, the 90 fixed rim may be of a shape which adapts it to receive a demountable rim.

The spoke ends may be joined or attached to the fixed rim in any desired manner adequate to the interlockment of the rim and spokes against relative displacement. So far as this invention is concerned it suffices to regard the fixed rim as seated directly upon the ends of the spokes, rather than the manner in which it is fastened thereto. In 100 other words, for the purposes of this case the manner in which the spokes are connected to the fixed rim may be disregarded except in the fact and to the extent that in the finished wheel the fixed rim is strongly tensioned 105 upon the body of the spokes and hence is in strong frictional engagement with the ends thereof.

As shown in Fig. 1, the wheel is supposed to be in a horizontal plane, that being the 110

most convenient position in which to assemble the spokes and the fixed rim and to act upon them in the upsetting press. It is feasible however to assemble the work in a vertical plane. In Fig. 1 the swaging press is represented by the circle of movable pressure jaws, J, assumed to act through limited distances along axes which converge at the center of the wheel and which serve to reduce the endless and initially oversized circular fixed rim, in the manner and for the purpose hereinafter detailed.

The construction of the wheel and the operation of the swaging press being now understood, my novel method may be considered. I begin with an endless metal fixed rim, 5, which is of an oversize, that is, of excessive circumference with respect to that size of pneumatic tire with which the particular wheel is to be used; and, also, prepare the correct number of wooden spokes, 3, in a length which is oversized or excessive with respect to the length they are to have in the finished wheel. In respect to the words, length of spoke, as used herein, it should be understood that the initial longitudinal dimension of each spoke may be of an actual over-length with respect to the size in which it is finished, or the same effect of overlength may be secured by making the mitered butts, 3, of the spokes wider than they will be when pressed together to form the hub center of the wheel. As a rule I observe both of these factors in preparing the spokes.

With the described parts at hand, I begin by assembling a full complement of the spokes, 3, in a single plane (which description includes a slightly dished condition) the inner ends of the spokes abutting throughout to form the hub-center of the wheel. This simple assembly of the spokes is a sufficient preparation for the application of the over-sized fixed rim. For wheels of other constructions and to insure greater uniformity therein a preliminary pressure is exerted upon every spoke to drive the mitered butts firmly together and take up differences in the density of the different pieces of wood from which the several spokes are made. Following this spoke-driving operation, and while holding them in compressed condition, I may next trim or shape the outer ends of the spokes to a uniform length or radius with respect to the wheel center (the added length of tenons upon the spokes is here disregarded) and I then apply the metal rim.

In whichever way they are assembled, the outer ends of the spokes define a circumference which is larger than will be defined thereby in the finished wheel. In other words, it still remains to drive the spokes farther toward the center of the wheel for the final sizing of the wheel and the final

consolidation of its hub center, and such action always takes place, although the actual final movement of the spokes may be so slight as to be hardly perceptible.

Having prepared the wheel body, that is, the group of radial wooden spokes, I then apply the endless metal rim, 5, thereto. If desired, the relative dimensions may be such as to require the exertion of force in order to lodge the body of spokes within the endless rim, or, if desired, the group of spokes and the rim may be accurately positioned in the swaging press or machine and the latter may be depended upon to force the rim, 5, into engagement with the ends of the spokes. In either case the rim and spokes are placed within the grasp of the circular group upsetting jaws, J, and the latter are then simultaneously driven inward, the force applied being sufficient to actually swadge or up-set of the metal rim until it is firmly lodged upon the ends of the spokes.

The pressure faces, J', of the jaws, J, together define the shape of the circumferential or perimetrical shape which the metal rim will have upon the completion of the inward movement of the jaws; I have found that if the pressure faces of the jaws conform to curves or arcs which cause them to coincide with a true circle common thereto at the moment of their arrival against the stops which limit inward movement, a very peculiar and detrimental action takes place in the metal rim immediately, or soon after, the jaws are retracted to permit the removal of the wheel, from the machine. Perhaps it will be obvious that as the jaws press upon the ends of the spokes either directly or through the medium of the encircling rim the ends of the spokes will be left at uniform distances from the true center of the wheel. Now when this same condition is to be observed in those parts of the fixed rim which form the arcs between the several spokes (and this would be the condition with the swaging faces of usual curvature) I find that all of the motion of the jaws is not fully or actually absorbed in the compressed metal, but on the contrary, upon release from the machine, the metal part expands or reacts to a considerable degree with an accompanying increase of circumference or loss of circumferential tension on the spokes and a perceptible tendency to spring outward from the ends of the spokes. It is extremely desirable that when the swaging operation is finished the metal rim shall be thereby left in a state of strong circumferential tension on the spokes and the expansibility of the metal tends to defeat the attainment of this object.

In my early experience with semi-wood wheels, I secured a nearly equivalent effect by performing the operation with the rim in a hot state and depending upon the final

shrinkage of the metal to overcome the objectionable reaction of the upset metal. Working with hot rims, while successful, is somewhat difficult, and it is the purpose 5 of this invention to render the hot operation unnecessary.

- I accomplish this by forcing the arcs (parts between the spokes) of the fixed rim farther toward the center of the wheel than 10 those parts which are in abutment with the spoke end; in other words, I subject the fixed rim to seemingly excessive compression and cause it temporarily to suffer an excessive loss of circumference, then upon releasing 15 the fixed rim from the swaging machine the ensuing reaction of the metal in the arcs accomplished no more than the restoration of the arcs to conformity with a true circle, and leaving the rim in a state 20 of strong circumferential tension, hence exerting heavy compression upon the body of spokes. Mechanically, these results are obtained by a change involving only a modification 25 of pressure faces of the jaws, J, which change consists in flattening the curves thereof so that when closed together the pressure faces of the circle of jaws present a generally polygonal shape, with the spoke contacts as the high points thereof. 30 The initial polygonal distortion of the normally circular fixed rim may be carried to such a point as to leave the arcs thereof perceptibly flattened, if the rim be one which is to receive a demountable rim, but 35 in the case of a fixed rim which must directly carry a pneumatic tire it is desirable

that the polygonizing of the rim be so limited as to insure the finishing of the wheel in as nearly as possible a truly circular form, without permitting such reaction as to yield 40 a wheel of more than the specified circumference.

Haying thus described my invention I claim as new and desire to secure by Letters Patent:

1. The herein described improvement in the art of manufacturing semi-wood wheels, comprising in general the forcible circumferential compression of the endless metal rim directly upon and until firmly seated 50 against the ends of the wheel-spokes with due conformity to true circularity, and in particular, consisting in simultaneously flattening the arcs of the rim (the portions between spokes) to an extent which prevents 60 the return of said arcs to or beyond the normal circumference, and whereby the rim is left in a state of strong circumferential tension upon the spokes.

2. The herein described improvement in 65 the art of making semi-wood wheels that consists in circumferentially upsetting the endless metal rim upon the ends of the spokes by means of compression jaws, each arranged or grouped between the spoke positions, and each conforming to a circle of greater radius than that which includes the ends of the spokes, substantially as and for 70 the purpose specified.

In testimony whereof, I have hereunto set 75 my hand this 20th day of November, 1919.

ERLE KING BAKER.
